FIG. 6.

UNITED STATES PATENT OFFICE

2,102,359

SANITARY GARMENT

Jacob G. Frieman, Attica, Ohio

Application November 5, 1935, Serial No. 48,404

7 Claims. (Cl. 128—289)

The present invention relates to sanitary garments and in particular to improvements in that general type disclosed in my U. S. Patent No. 1,924,642, granted Aug. 29, 1933.

5 In the prior construction above referred to, strap members were employed of an adjustable character and associated with the napkin or pad holding section and these not only had a tendency to place undue stresses at particular points, but 10 they had a tendency to show strap lines when worn with thin apparel.

The present pantie form of my invention, eliminates the use of straps or bands as means of support, is designed to fit more smoothly and un- 15 noticeably, embodies an improved form of pocket, and markedly facilitates replacement and retention of the absorptive pad used therewith, while affording the desired protection and shielding of the body parts.

20 Another object of my invention is to provide a pantie of the above class in which the pocket for the absorptive pad may be opened longitudinally to facilitate the replacement of the pad without the removal of the pantie from the wearer, or 25 loosening of garments worn thereover.

Other and further objects and advantages of the invention will be hereinafter set forth and the novel features thereof defined by the appended claims.

30 In the drawings:

Fig. 1 is a view in front elevation showing the garment as worn;

Fig. 2 is a rear view;

Fig. 3 is an enlarged fragmentary view looking 35 at the interior of the crotch or pad holding section in plan;

Fig. 4 is a transverse sectional view on the line 4—4 of Fig. 3;

Fig. 5 is a fragmentary longitudinal sectional 40 view about on the line 5—5 of Fig. 3.

Fig. 6 is an enlarged fragmentary bottom plan view showing a modified embodiment;

Fig. 7 is an enlarged section on line 7—7 of Fig. 6; and

45 Fig. 8 is a view similar to Fig. 6, but showing a further modification.

Like reference characters refer to like parts in the several figures of the drawings.

Specifically describing the invention, the body 50 portion thereof is of pantie form of suitable thin knitted or netted material, as indicated at 1, adapted to fit closely and snugly around the body of the wearer at the hips and having preferably a narrow elastic band 2 about the top thereof.

55 Preferably also, this body section is openable at

one side, at least partially, the opening 2a having the desired button or snap closures 3.

The type of fabric material referred to is capable of stretching to a great extent and readily resuming its normal contracted form, so as to 5 always insure a close or snug fit to different forms while being very cool because of its open work character. Garments may be worn over this without discomfort or materially showing the lines thereof, which is a desideratum of importance in view of the present day dress.

The body section 1 is connected to the crotch section 4 which forms the pad holding portion proper, the lines of connection being curved along the seams 5 and 6. By forming this crotch section 15 of complementary longitudinal sections 4a and 4b, a pocket 7 may be let into the central seam, which by its fullness will provide an elongated free holding container for a conventional form of sanitary napkin,—free in the sense of not being constricted or compressed by the stresses applied to the surrounding sections of material by the body portion 1. In this way, the pad 8, which, of course, may be of any suitable material, when inserted in the pocket will be free from normal 20 compressive stresses, so as to best perform its 25 absorptive functions.

At each end of the pocket is attached a fabric retaining strip 9 which makes a small end pocket to receive the end of the napkin, securely holding 30 the latter removably in place. To replace the napkin when desired, one of the ends is slipped out, whereupon it may be easily pulled out of the main pocket 7, and a fresh one placed therein.

It is to be understood that the material of the 35 crotch section, including that of the pocket, is preferably rubberized, at least on one side, namely, that opposite the surface which contacts with the flesh. The sections 4a and 4b constitute protective flaps which are designed to prevent soiling 40 of the parts of the limbs adjacent to the pad. The seams 5 and 6, the central connecting seam 4c and that surrounding the pocket 4d, are all preferably machine whipped to reinforce the same so as to prevent tearing or rupture and prevent 45 any tendency to pull the crotch section out of normal shape. By virtue of this form of seam around the edges of the pocket, said pocket will remain loose and full to freely accommodate the absorptive material without compression as ex- 50 plained above.

The foregoing garment is a single unit without adjustable strap elements and requires no pins or similar fastenings which might accidentally come loose and allow unintentional displacement 55

of the pad. Being of washable material it may be effectively cleansed and maintained in a sanitary condition.

Figure 6 discloses a construction in which the pocket for the reception of the absorptive pad is indicated at 10, and is slit longitudinally as at 11, the free edges of the pocket having secured thereto a separable fastener 12 provided with the usual operating slide member 13.

10 A protecting flap member 14 is secured to one edge of the opening formed by the slit and projects across the same above the fastener to overlap the slit and the fastener, as clearly seen in Fig. 7 of the drawings.

15 With this construction it is not necessary to either loosen the corset, girdle or other garment under which it is worn or to remove the pantie from the wearer in order to replace the absorbent pad member 15, since by moving the slide member 20 13 to the other end of the separable fastener 11 the interlocking portion of the fastener will be released in a well known manner, thus opening the slit 13. The soiled pad may then be removed and a fresh one inserted without the necessity or 25 inconvenience of loosening or removing the pantie.

It is obvious that a very quick and convenient replacement of the pad can thus be accomplished. The overlapping flap member 14 efficiently closes 30 the opening between the edges of the slit in the pocket and also protects the separable fastener from being soiled by the pads. The remainder of the construction, as shown in Figures 6 and 7, is the same as in the preferred embodiment and 35 therefore the same reference numerals are used on these parts.

Fig. 8 also discloses a pantie in which the pad retaining pocket is openable longitudinally in order that a pad may be inserted without removal 40 of the pantie, but in this form of the invention the complementary side portions of the pocket, as indicated at 16 and 17, are made wider so as to lay in overlapping relation when in use, as clearly seen in this figure of the drawing. The 45 side portion 16 is provided throughout its length with button holes or similar openings 18 for the reception of buttons or other securing means 19 similarly disposed on the other side member 17.

While in Fig. 8 I have disclosed buttons for 50 securing the sides 16 and 17 of the pocket together, I contemplate the use of the well known snap fasteners in their place if I so desire.

I claim:

1. A sanitary garment of the class described, 55 comprising a stretchable body of pantie form, said body having a closed crotch section of non-stretchable waterproof material, said section being formed with a fulled central longitudinal pocket let into the center, the edges of the pocket 60 being so connected to the surrounding crotch section material that the stretching stresses are resisted and distortion of the pocket prevented.

2. A sanitary garment of the class described, 65 comprising a fabric body of pantie form adapted

to snugly fit the body of the wearer, said pantie body having a closed crotch portion composed of complementary sections seamed centrally, a shallow fulled pocket let into the seam so as to be free from compressive stresses, and strips attached to the ends of the pocket to form small retaining end pockets to receive the ends of a conventional sanitary napkin, the crotch sections surrounding the pocket forming side protective flaps to cover parts of the body adjacent the 10 napkin.

3. A sanitary garment of the class described comprising a stretchable body of pantie form, said body having a closed crotch section of non-stretchable waterproof material, said section being formed with a fulled central longitudinal pocket split longitudinally to form a bottom opening, and a separable fastener for securing the edges of the slit together, the outside edges of pocket 15 being so connected to the surrounding crotch section by a reinforcing seam that the stretching stresses are resisted and the distortion of the pocket is prevented.

4. A sanitary garment of the class described comprising a fabric body member having a closed 20 crotch portion formed with a central pad receiving pocket attached to the crotch portion by a fulling reinforcing seam, said pocket being formed with a longitudinal opening for the removal of a 25 pad from said pocket through said opening.

5. In a sanitary garment, a supporting body 30 having a closed crotch portion formed with a sanitary pad receiving pocket attached to the crotch portion by a fulled reinforcing seam, said pocket being split longitudinally to permit the 35 removal of a sanitary pad therethrough, closure means on the edges of the slit, and a protecting flap member extending across said opening above said closure means.

6. In a sanitary garment of the class described, 40 a supporting body having a closed crotch portion formed with a non-stressed sanitary pad receiving pocket attached to the crotch portion by a reinforcing seam, said pocket comprising a pair 45 of longitudinally disposed overlapping flap members each secured at one edge to the body and means for detachably retaining the overlapping portion of the flap members together, said last means comprising a fastener device carried by one of said flap members, and a second fastener carried by the other flap member for detachable co-operation with the aforementioned fastener device on the first flap member.

7. In a sanitary garment, a supporting body 55 having a closed crotch portion formed with a non-stressed sanitary pad receiving pocket attached to the crotch portion by a reinforcing seam, said pocket being split longitudinally to form a pad removal opening, a separable fastener 60 for closing the free edges of said opening and operative means for said fastener disposed exteriorly of said pocket.

JACOB G. FRIEMAN.
